UNITED STATES PATENT OFFICE.

FREDERICK W. PETERS, OF WEST PARK, OHIO, ASSIGNOR TO THE PARAGON MACHINE, TOOL & MANUFACTURING COMPANY, OF CLEVELAND, OHIO, A CORPORATION OF OHIO.

VISE.

1,323,647.

Specification of Letters Patent.

Patented Dec. 2, 1919.

Application filed May 11, 1918. Serial No. 233,981.

To all whom it may concern:

Be it known that I, FREDERICK W. PETERS, a citizen of the United States, residing at West Park, in the county of Cuyahoga and 5 State of Ohio, have invented a certain new and useful Improvement in Vises, of which the following is a full, clear, and exact description, reference being had to the accompanying drawings.

10 This invention relates to clamping devices, such as vises, and has for its general object so to construct and operate the movable member thereof as to enable the convenient and positive manipulation of such 15 part for the purpose of clamping and unclamping various articles upon which it is to operate.

A further and more limited object of the invention is to provide a device of this character with means whereby the movable jaw may be conveniently brought into operative relation with the article to be clamped, after which it may be further and more securely clamped against such article through the 25 manipulation of the handle and may afterward be disengaged from such article and opened in an extremely effective and convenient manner. I secure these objects in and through the construction and arrangement of parts illustrated in the drawings forming part hereof wherein Figure 1 represents a central longitudinal sectional view through a vise embodying my invention, certain parts being shown in elevation and the 30 pawl being shown in locking position; Fig. 2 is a view corresponding to the line 2—2 of Fig. 1 and looking in the direction of the arrows. Fig. 3 a longitudinal sectional view corresponding substantially to the line 35 3—3 of Fig. 2 and looking in the direction of the arrows, the parts being shown in pawl-disengaging position; and Fig. 4 a perspective view of the pawl which coöperates with the movable jaw of the vise.

40 Describing by reference-characters the various parts illustrated herein, 1 denotes the base or bed-plate of the vise, said base or bed-plate having at one end thereof a vertical projection 2 forming a support for the fixed jaw 3. The bed-plate is provided with a ratchet or rack 4, secured in any convenient manner within a recess extending longitudinally of the bed-plate and located about midway between the sides of such bed plate, 45 the said ratchet or rack having teeth 5 ex-

tending transversely of the bed-plate; each tooth being shown as provided with a vertical shoulder 5^a and an inclined surface 5^b extending downwardly from the upper end of such shoulder and toward the end of the 60 rack remote from the jaw 3.

On each side of the rack 4, the bed-plate is provided with a vertical slot. Each slot consists of three portions of varying width, the upper portion 6 being the narrowest, the portion 6^a therebeneath being somewhat wider than the portion 6 while the lowest portion 6^b of the slot is shown as considerably wider than the portion 6^a. The slot portions 6 form guides for tongues 7^a projecting downwardly from and preferably formed integral with the movable member 7 of the vise, said movable member being provided with a movable jaw 8. Coöperating with each tongue 7^a is a removable 75 extension 9, the upper portion of such extension being shown as of substantially the same width as the tongue whereby it may slide freely with the slot portion 6^a and the lower portion of each such extension being 80 enlarged to provide an elongated head 9^a the upper lateral edges whereof are adapted to engage beneath the shoulder 6^c while the head is free to slide within the slotted portion 6^b. The extensions 9 are detachably 85 connected to the main body 7 of the movable vise member, as by means of lag screws 10 threaded into the tongue 7^a and the lower portion of such body. The construction including the tongues 7^a and the extensions 9 90 enable the member 7 of the vise to be moved toward and from the fixed jaw 3 and to be guided and positioned accurately during such movement.

The movable member 7 is provided with 95 a chamber 11 projecting upwardly from the bottom thereof, said chamber being located between the tongues 6 and providing side walls 7^b, a rear wall 7^c and a front wall 7^d extending transversely of said member, the 100 jaw 8 being secured to the last mentioned wall. The bottoms of the walls 7^b and 7^c and the bottoms of the sides of the movable member are adapted to slide upon the bed plate 1.

105 The walls 7^c and 7^d are provided with cylindrical apertures constituting bearings for a screw shaft 12, the front end 12^a of said shaft being shown as of smaller diameter than the rear end and a collar 12^b being de- 110

tachably connected, as by a pin 13, to the said shaft immediately in front of the rear bearing. Between the bearings, the body of the shaft is provided with a heavy thread 5 12°, constituting a screw.

Mounted on the screw is a nut comprising an inner internally threaded bushing 14, having a flange 14^a at its rear end, and an external rectangular sleeve 15, the said bushing having a driving connection with said sleeve whereby the bushing and sleeve will move in unison through the rotation of the screw. The sleeve 15 is provided with a pair of trunnions 15^a projecting laterally from the central portion thereof, said trunnions 10 forming a bearing for a pawl. This pawl may be conveniently formed of two symmetrical members 16, each comprising an arm having a bushing 16^a whereby it may be applied to a trunnion, the lower end of each 15 arm having a projection extending at right angles to the body thereof, as indicated at 16^b, the portions 16^b constituting the pawl proper and the pawl members being connected by means of a bolt 17 fitted in one of such lateral projections 16^b and threaded into the other. The lower end of this pawl is adapted to coöperate with the rack or ratchet 20 teeth 5.

30 A pair of pins 18 are mounted in the base of the movable member 7, each projecting inwardly above and on opposite sides of the rack 4 and immediately above the same. These pins coöperate with the pawl in a manner to be described hereinafter.

35 The rear end of the screw shaft is provided with a clutch collar 19 coöoperating with the collar 13 to prevent relative longitudinal movement between the screw and the movable vise member. Rotatably mounted on the rear end of the screw shaft is a 40 handle 20, said handle being movable along the shaft and having a clutch member 21 adapted to coöperate with the clutch collar 19 to provide a driving connection between 45 the handle and the screw shaft.

With the parts constructed and arranged as described the operation will be as follows: An article having been inserted between 50 jaws 3 and 8, the movable member including the jaw 8 may be slid by hand upon the bed plate 1 until the jaw 8 is in substantial engagement with such article, the pins 18 traveling with said movable member and the 55 pawl riding over the teeth of the ratchet or rack. The operator then grasps the handle 20, moving it into driving relation to the clutch member 19 and with a left-handed screw such as shown in the drawings, turns 60 the handle in a counter-clockwise direction. If the pawl proper is not in actual engagement with the vertical shoulder of a tooth the rotation of the screw will impart a backward movement to the nut 14, 15 until such 65 time as the pawl abuts against such shoulder

to lock the nut against movement. Further movement of the nut is suspended by such engagement and further rotation of the screw causes the movable member to be thrust forwardly, the screw being rotated 70 until the article is firmly clamped between the jaws 3 and 8, the position of the parts being shown in Fig. 1. When it is desired to release the article, the handle 20 is rotated in the opposite direction. This causes the 75 nut 14, 15 to move forwardly upon the screw and, before the nut shall have reached the front end of the chamber 11, the pins 18 will have engaged the arms 16 respectively thereabove to trip the pawl, as shown in Fig. 3. 80 The operator can then grasp the movable member and move the same rearwardly by hand, the pawl being lifted clear of the rack teeth. The pawl may be set in operative relation to the rack merely by revolving the 85 handle 20 in the appropriate direction.

It will be seen that the pawl, the ratchet or rack, the pins 18 and the screw 12 afford means by which the movable clamping member may be locked against rearward movement in any position to which it may have been adjusted toward the fixed clamping member 3; also that, when the movable clamping member shall have been adjusted by hand to approximate clamping position, 95 further movement of said movable clamping member is obtained through relative motion between the pawl or locking member, through the nut and the movable clamping member; also, that, through relative movement in the reverse direction between the pawl and the movable clamping member, the pawl is automatically unlocked, permitting the movable member to be operated in the reverse direction by hand—and that the 100 screw 12 and nut 14, 15 constitute the means for securing the reverse relative movements between the pawl and the movable clamping member.

As rust or the accumulation of sediment 110 may prevent the pawl from dropping into place when released from the pins 18, I have interposed a spring 22 between each arm or member 16 of the pawl and the guideway formed thereabove by the side of 115 the top of the chamber 11 and the side wall 7^b thereof, the top of said chamber has a central depressed portion 15^b coöperating with the nut sleeve 15 and also coöperating with the walls 7^b to form said guideways. 120 The springs 22 are preferably of flat metal, shaped as shown and secured to the pawl arms by screws 23.

For convenience of description, the element 5 has been referred to herein as a 125 "rack." It will be understood that, by the use of such specific description, I do not propose to be limited to any particular style of locking device coöperating with the pawl; nor do I propose to limit my inven- 130

tion except as such limitations may appear in the claims hereto annexed or may be rendered necessary by the state of the prior art.

5 Having thus described my invention, what I claim is:—

1. In a device of the character described, the combination of a bed, a pair of clamping members carried by said bed, one of 10 said members being movable toward and from the other, a screw carried by such movable member, a nut mounted on said screw and provided with a pair of trunnions, a pawl having arms pivoted on said trunnions, a rack carried by said bed and 15 coöperating with said pawl, and a pair of pins carried by the movable member and each projecting beneath an arm of said pawl and adapted to engage such arm through the 20 movement of the nut along said screw.

2. In a device of the character described, the combination of a bed, a pair of clamping members mounted thereon one of said members being movable toward and from 25 the other, a screw supported by the movable member, a nut comprising an internally threaded bushing mounted on said screw, and a sleeve surrounding said bushing and provided with a support, a branched pawl 30 pivoted on said support, a rack having inclined teeth mounted on said bed in operative relation to said pawl, and a pawl-engaging device carried by such movable member and extending between the pawl 35 and the rack and adapted to disengage the pawl from the teeth of said rack when the said nut shall have traveled a predetermined distance on said screw.

3. In a device of the character described,

the combination of a bed, a pair of clamping members carried by said bed, one of 40 said members being movable toward and from the other, a screw carried by such movable member, a nut mounted on said screw and provided with a pair of trunnions, a pawl having arms journaled on said trunnions, a rack carried by said bed and coöperating with said pawl, a pair of pins 45 carried by the movable member and each projecting beneath an arm of said pawl and adapted to engage such arm through the movement of the nut along said screw, and a spring coöperating with each arm of said pawl and tending to move the pawl into engagement with said rack. 50

4. In a device of the character described, the combination of a bed, a pair of clamping members mounted thereon, one of said members being movable toward and from the other, a screw supported by the movable 60 member, a nut comprising an internally threaded bushing mounted on said screw and a sleeve surrounding said bushing and provided with trunnions, a pawl having arms journaled on said trunnions, a rack 65 mounted on said bed in operative relation to said pawl, pawl-engaging devices carried by such movable member and extending between the arms of the pawl and the rack and adapted to disengage the pawl from 70 the teeth of said rack when the said nut shall have traveled a predetermined distance on said screw, and a spring coöperating with said pawl and tending to move the pawl into engagement with said rack. 75

In testimony whereof, I hereunto affix my signature.

FREDERICK W. PETERS.
